UNITED STATES PATENT OFFICE.

EMMONS W. BONFIELD, OF GRAND RAPIDS, MICHIGAN, ASSIGNOR TO AMERICAN BOX BOARD COMPANY, OF GRAND RAPIDS, MICHIGAN, A CORPORATION OF MICHIGAN.

FOLDING BOX OR SHIPPING-CASE.

1,188,401.

Specification of Letters Patent. Patented June 27, 1916.

Application filed August 4, 1915. Serial No. 43,835.

To all whom it may concern:

Be it known that I, EMMONS W. BONFIELD, a citizen of the United States of America, residing at Grand Rapids, in the county of Kent and State of Michigan, have invented certain new and useful Improvements in Folding Boxes or Shipping-Cases; and I do hereby declare the following to be, a full, clear, and exact description of the invention, such as will enable others skilled in the art to which it appertains to make and use the same.

This invention relates to a folding box or shipping case especially adapted for the transportation of a large number of shoe boxes.

It is the object and purpose of the invention to provide a case of this character which may be made from fiber board or the like and of the size sufficient to contain a large number of boxes of shoes yet which will not buckle or otherwise distort under the weight of the merchandise which it contains. In practice this shipping case is first used to ship from the manufacturer to the wholesaler. After it reaches the wholesaler it is necessary to sort the boxes of shoes to supply the demands of the retail trade and my invention is designed to satisfy the conditions and overcome the difficulties which are met in this instance particularly.

The various constructions and arrangements of parts which are used in the embodiment of my invention together with the novel and useful features of construction and operation coming therefrom, will be apparent as fuller understanding is had of the construction shown in the accompanying drawings, in which;

Figure 1 shows the two parts of my folding shipping case in collapsed condition so as to occupy little space for transportation when sent from the manufacturer to the user. Fig. 2 illustrates in perspective the shipping case as it appears previous to placing articles of merchandise therein, one side of the case being open. Fig. 3 is a perspective taken from in front and above the shipping case after it is closed and showing the method of sealing the case. Figs. 4 and 5 are perspective views of the inner and outer members of the case, respectively; and Fig. 6 shows in perspective, 55 the positions of the inner and outer parts

of the case that will be resorted to during the process of sorting boxes of shoes in the case.

Like reference characters refer to like parts throughout the several views of the drawings.

My shipping case comprises in its construction an inner and outer member, the outer member including a side 1, an end 2 bent at right angles therefrom, a side 3 bent parallel to the side 1 and an end 4 bent at right angles from the side 3 and parallel to the end 2 terminating in an extension 5 that lies against the inner side of the side 1 and to which it is secured by staples or other suitable fastenings. Flaps 6 project from one edge of each of the sides and ends 1, 2, 3 and 4. The inner member also contains a side 7, an end 8 bent at right angles therefrom, a side 9 parallel to the side 7 and an end 10 bent at right angles to the side 9 and parallel to the end 8, this end 10 also having an extension 11 similar to the extension 5 previously described and which is secured to the side 7 as extension 5 is secured to side 1. Flaps 12 project from one edge of each of the sides 7, 8, 9 and 10 of this member. A horizontal partition 13 is located between the ends 8 and 9 having at each end thereof right angular extensions 14 and 15 which are permanently fastened by means of staples or other suitable connections to the sides 7 and 9 as shown in Figs. 2, 4 and 6.

It will be noted that at the junction of the sides 1 and 3 with the ends 2 and 4 and also of the sides 7 and 9 with the ends 8 and 10 a corner is formed consisting of a narrow strip 16 which is offset a slight distance from said sides and ends, there being a double bend in making the right angular turn from a side such as 1 to an end such as 2. This permits the ready folding of the members of a shipping case as shown in Fig. 1 so that they occupy little or no space. Furthermore, a similar construction is made where the flaps 6 and 12 join the sides and ends of the case members, the narrow strip 17 being constructed in all respects similar to the strip 16 while at the ends of partition 13 a similar strip 18 joins this partition with its extensions 14 and 15. By reason of this construction not only do the case members readily collapse but

the flaps may be turned to close an open front or back of a shipping case member and this without undue strain being imposed upon the material composing the members 5 as would be the case if a single right angular bend was made between the parts composing the shipping case members. Also sufficient space is provided especially in the inner member to permit the ready collapsing 10 of said member with the partition 13 between the sides thereof and without making the inner portion of said member when collapsed thicker than at the ends, as fully illustrated in Fig. 1.

15 In the use of a shipping case the flaps 12 of the inner member are closed and retained in position by means of sealing tape or the like overlapping the adjacent edges of the outer flaps. The outer member may 20 then be telescoped over the inner member and boxes of shoes positioned in the inner member to fill the upper and lower compartments. The dimensions of the inner member are such that the outer member may 25 be passed over it, sides 1 and 3 lying outside of sides 7 and 9 and similarly ends 2 and 4 outside of ends 8 and 10.

The box or case when filled is closed and sealed by means of sealing tape 19 from 30 the roll 20 connecting the edges of sides 1 and 3 and ends 2 and 4 with the flaps 12 of the inner member.

It will be noted that when the shipping case is filled or being filled with articles of 35 merchandise it is strongly reinforced at the sides and ends, there being a double thickness of material at both the sides and ends while the flaps 6 and 12 partially overlapping each other reinforce the top and bottom 40 of the box.

In shipping a lot of shoes from the manufacturer to the wholesaler, a single shipping case will usually contain one size of a certain style or at least a few sizes of a single 45 style. The wholesaler in order to supply his trade must ship a greater variety of sizes and styles in a single case. It is necessary, accordingly, that when the case reaches the wholesaler that it be opened and the goods 50 sorted to supply a particular order of the retailer. To do this the sealing tape binding the two members together is cut and the outer member removed, being then positioned over the inner member from the rear 55 thereof as shown in Fig. 6. It is necessary to do this in order to provide the proper strength and rigidity to the shipping case. In the operation of sorting shoes for instance, if part of the shoes are taken from 60 the lower compartment and part from the upper compartment there will be a tendency of the sides 7 and 9 to buckle or distort which is resisted by the sides 1 and 3 of the outer member; any attempted distortion of 65 the shipping case is in this manner overcome

and taken care of by reason of the particular construction of the members of the case and the telescoping properties which they have with respect to one another. After the goods have been sorted and the case filled 70 with the desired numbers and styles it may be again sealed as before and shipped by the wholesaler to the retailer.

From the foregoing it will be apparent 75 that I have provided a very useful construction of shipping case and one which may be made of light material such as fiber board or the like and collapsed to occupy little or no space when sent by the manufacturer of the case to the wholesaler who will use it. 80 Furthermore by reason of the construction outlined, a very serviceable and durable case is made and one readily adapted to withstand the rough usage to which it may be subjected in transportation from one place 85 to another.

Various modifications in minor detail may be resorted to without departing from the invention defined in the appended claims and all modifications falling within the 90 scope of said claims are to be considered as comprehended within my invention. And while in the foregoing description the shipping case has been referred to as especially useful in holding shoe boxes or cartons, it 95 is of course understood that it is not limited to such use but may be utilized in the shipping and carrying of many other and various articles of merchandise.

I claim:-

1. A shipping case comprising an outer member having sides and ends with flaps extending from one edge of each of the sides and ends, an inner member similarly constructed of sides and ends with flaps extending from one edge of each of said sides and ends, and a partition located between and connected at its ends to the sides of the inner member, said inner member being of a size to be received within the outer member. 100

2. A shipping case comprised of inner and outer members, each formed from a single piece of material and comprising sides and ends with flaps extending from one edge of said sides and ends, the sides, ends and flaps 105 of each member being joined together by a hinge-like joint to permit relative movement of said parts with respect to each other, said inner member being slightly smaller than the outer member permitting it to be 110 received therein, and a partition lying between the sides of the inner member at each end having extensions turned at right angles and hinged to the partition and secured to the sides.

3. A shipping case comprised of inner and outer members, each formed of a single piece of material and comprising sides and ends with flaps extending from one edge of said sides and ends, and a hinge-like joint be- 115

tween the sides and ends, said joint comprised of a double bend in the material with a narrow strip of material located between the said bends and positioned normally at an obtuse angle to said sides and ends, said inner member being slightly smaller than the outer member so as to be received therein, substantially as described.

4. A shipping case comprised of inner and outer members, the inner member adapted to be received within the outer member, each member being formed from a single piece of material and comprising sides and ends with flaps extending from one edge of said sides and ends, a hinge-like joint between the ends of connected sides and ends comprised of a double bend in the material with a narrow strip of material located be-

tween the bends, a similar hinge-like joint between the flaps and the sides and ends to which they are connected, a partition located between the sides of the inner member having an extension at each end thereof, said extensions projecting in opposite directions and secured to the sides of the inner member, and a hinge like joint between the partition and the extensions thereto similar to the joint between the sides and ends of the member, substantially as described.

In testimony whereof I affix my signature in presence of two witnesses.

EMMONS W. BONFIELD.
